UNITED STATES PATENT OFFICE.

ETHAN ROGERS, OF BALLSTON, NEW YORK.

METHOD OF MAKING TOOL-BLANKS.

SPECIFICATION forming part of Letters Patent No. 623,384, dated April 18, 1899.

Application filed July 11, 1898. Serial No. 685,592. (No specimens.)

To all whom it may concern:

Be it known that I, ETHAN ROGERS, a citizen of the United States, residing at Ballston, county of Saratoga, and State of New York, have invented certain new and useful Improvements in Methods of Making Tool-Blanks, of which the following is a specification.

The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

Figure 1 of the drawings is a side elevation of a bar-plate from which pieces are cut to be formed into blanks. Fig. 2 is an end view of the same. Fig. 3 is a side elevation of a cut-off piece standing on one end. Fig. 4 is a top plan view of a two-part forming-die. Fig. 5 is a side elevation of the same with the front part removed and showing a cut piece of the bar-plate in position to be formed by the forming-die, shown in elevation above the piece. Fig. 6 is a side elevation of a cut-off piece 30 formed ready for punching, showing the convexed edge uppermost. Fig. 7 is a top plan view of the two-part gripping-die. Fig. 8 is a side elevation of the same with the front part removed and showing the formed piece 35 in position therein to be punched by the punch shown in part just above the formed piece. Fig. 9 is a view in side elevation of the finished blank. Fig. 10 is an upper edge view of the same.

The dies and punch herein shown and described may be operated in a machine like that shown in United States Letters Patent No. 531,221, issued to me December 18, 1894, for improvements in machines for making ax-polls, to which patent reference may be had for a description thereof.

My improved method is especially adapted for use in making ax-poll blanks where pieces to form blanks are cut from a rolled bar-plate 50 of steel and in which pieces an eye is formed by punching a comparatively long distance

edgewise through the relatively thin plate from one cut edge to the other.

A is the bar-plate, rolled from the beveled bit portion A' of the blanks and the remaining body or head portion adapted to receive the eye E. The bar-plate is highly heated at one end and a piece A², adapted to form a blank, cut off along the dotted line A³ in Fig.

1. If this piece in its cut-off form were placed in gripping-dies and punched, those portions adjacent to the punch would follow the parts forced along before the punch sufficiently to distort the piece and form an imperfect blank and render it difficult or impossible to afterward remove the imperfections. I have ascertained that the heated and yielding piece of metal can be easily given a form preparatory to punching, such that the punching operation is not only facilitated, but the piece 60 easily and naturally assumes during the operation the form of a perfect blank. I insert the piece A² in a two-part female section B of a forming-die and form the piece by pressure thereon of the male section B'. It will be 65 seen in Fig. 5 that the bottom of the die is provided with a concaved surface B² and that one of the upright walls B³ is beveled upwardly and outwardly. The formed piece upon emerging from this die has the form 70 seen in Fig. 6, where it is shown in an inverted position, for the reason that the convexed side B⁴ should be uppermost to receive a descending punch and the recess B⁵ formed by the projection B⁶ on the lower side. 75 The formed piece is then inserted in the two-part section or grippers C of the punching-die in the position shown in Fig. 8. The punch P is then forced down through the upper convexed edge to form the eye E. As 80 the punch passes down through the comparatively thin piece of metal the sides of the piece are held up to place and form by the side walls and projections C' of the grippers. The convexity of the upper edge of the piece 85 is approximately sufficient to permit the natural drop of the edge during the punching operation without producing a convexity of the edges in the punched blank. The recess on the lower edge receives most of the metal 90 displaced by the punch and prevents undue strain upon the punch and die which would

- take place if the displacement were wholly compensated for by forcing the surrounding metal to flow upward within the die. There being some expansive flow of the metal forwardly in the direction of the bit between the gripping projections C' C', there would be a very great forward lateral strain upon the punch if the back edge had no corresponding vent.
- 10 By giving the formed piece the upward inward bevel B⁷ sufficient expanding room is afforded to reduce the lateral strain upon the punch to a minimum. Furthermore, the beveled back edge and convexed upper edge combine to produce at the end of the punching operation a full square corner at the junction of the back and upper edge, as seen in Fig. 9, whereby I am enabled to produce a perfect blank at the conclusion of the punching operation without subsequently swaging. The eye can be fully formed by inverting the blank in the same dies and inserting the punch through the edge which was previously at the bottom.
- 15 When desired, the stock P', which supports the punch, may be given the function of a pressing-die and employed to give to a limited degree the upper and lower edges of the blank a more accurate and exact form.
- 20 When convexing and concaving the blank, as shown in Fig. 5, it is in most cases unnec-
- 25
- 30

essary to support the sides or ends of the blank, it being sufficient to press the cut-off piece between the projection B⁶ and the concaved bottom B². The wedging force of the projection is sufficient to force the upper part of the head edge outwardly to form the bevel B⁷ without the support B³.

What I claim as new, and desire to secure by Letters Patent, is—⁴⁰

The method of making tool-blanks which consists in heating and preparatorily forming by pressure, a metallic bar-plate blank whereby its upper edge is provided with a longitudinally-convexed surface extending from the front to the back edges, and its lower edge with a recess intermediately of its front and back edges, and afterward filling the recess by forcing a portion of the convexed edge downwardly by means of an eye-forming punch, and at the same time forcing the un-punched convexed portion downwardly to an approximately horizontal plane, and completing the eye-aperture by forcing the punch through the blank, substantially as described. ⁴⁵ ⁵⁰ ⁵⁵

In testimony whereof I have hereunto set my hand this 2d day of July, 1898.

ETHAN ROGERS.
